UNITED STATES PATENT OFFICE.

CHARLES F. JONES, OF BLANCHETT, KENTUCKY.

SHADE-ROLLER.

SPECIFICATION forming part of Letters Patent No. 633,009, dated September 12, 1899.

Application filed May 13, 1899. Serial No. 716,784. (No model.)

To all whom it may concern:

Be it known that I, CHARLES F. JONES, a citizen of the United States, residing at Blanchett, in the county of Grant and State of Kentucky, have invented certain new and useful Improvements in Shade-Rollers; and I do declare the following to be a full, clear, and exact description of the invention, such as will enable others skilled in the art to which it appertains to make and use the same.

The invention has relation to vertically-adjustable shade-rollers.

The object of the invention is to provide simple, inexpensive, and effective means for lowering or hoisting the shade-roller, so as to admit light and air over the top of the curtain and at the same time permit of the adjustment of the curtain upon its roll.

With this object in view the invention consists in certain features of construction and combination of parts, as will be hereinafter fully described and claimed.

In the drawings, Figure 1 is a view of a window-frame illustrating the application of my invention, the shade-roller being shown in its elevated position and the shade partially drawn. Fig. 2 is a similar view, the roller being shown in its lowered position with the shade drawn.

In the drawings, 1 denotes the window-frame, and 2 denotes a shade-roller of the Hartshorn type. This roller is supported in brackets 3, secured to a cross-rod 4.

5 denotes two systems of lazy-tongs levers the lowermost levers of each system being connected to the cross-bar, while the uppermost levers of each system are pivoted upon a screw or stud 6, and one of each set of the uppermost levers has an extension or arm 7, the upper ends of which are pivoted to the upper cross-bar 8.

9 denotes an operating-rod working through the vertical aperture 10 in the bracket 11 and held in adjustment by a set-screw 12. The upper end of this bracket-arm is pivoted 45 to the laterally-projecting arm of one of the extensions 7.

In operation, assuming the shade-roller to be in the position shown in Fig. 1 and it be desired to lower the shade-roller, the set-screw 50 12 is loosened and the operating-rod moved upward. This will cause the levers of each lazy-tongs system to distend, and the roller with its shade will be lowered to any desired position—such as, for instance, the position shown 55 in Fig. 2—in which position it may be securely retained by clamping the set-screw firmly against the operating-rod. A reverse movement of the operating-rod will raise the roller with its shade.

It will be noticed that but a slight movement of the operating-rod is necessary to move the roller from the position shown in Fig. 1 to that shown in Fig. 2.

Having thus described the invention, what 65 is claimed, and desired to be secured by Letters Patent, is—

The combination of a lower rod, shade-roller brackets secured thereto, systems of lazy-tongs levers connected to the said rod, one of 70 the upper levers of each system having an extension, an upper cross-rod connecting the said extensions, and an operating-lever for actuating the systems of levers, substantially as and for the purpose set forth.

In testimony whereof I have hereunto set my hand in presence of two subscribing witnesses.

CHAS. F. JONES.
